UNITED STATES PATENT OFFICE

2,444,107

FLASHLIGHT

Marvin E. Montgomery, Canton, Kans.

Application December 17, 1946, Serial No. 716,870

4 Claims. (Cl. 240—10.6)

1

This invention relates to a flashlight and has for its primary object to produce a powerful light beam.

Another object is to facilitate the handling of the flashlight and the rapid lighting or extinguishing of the lamp thereof.

A further object is to facilitate the adjustment of the lamp bulb with relation to the reflector in order to produce a beam of maximum intensity.

The above and other objects may be attained by employing this invention which embodies among its features a plurality of spaced parallel tubes arranged symmetrically about a longitudinal axis, a base joining and closing said tubes at one end of the group, a head joining the tubes at the opposite end of the group, a hood detachably mounted on the head, a window in said hood in alignment with the axis about which the tubes are grouped, an incandescent electric lamp mounted in the head for adjustment along the longitudinal axis thereof, and power supply means within the tubes for supplying electrical energy to the lamp.

Other features include a switch carried by the head in axial alignment with the lamp selectively to energize and deenergize the lamp.

In the drawings:

Figure 1 is a side view of a flashlight embodying the features of this invention.

Figure 2 is an end view of Figure 1.

Figure 3 is a transverse sectional view taken substantially along the line 3—3 of Figure 1.

Figure 4 is an enlarged end view showing the hood removed.

Figure 5 is a sectional view taken substantially along the line 5—5 of Figure 3.

Figure 6 is a detailed plan view of the contact plate.

Figure 7 is an enlarged fragmentary view partially in section, taken substantially along the line 7—7 of Figure 4.

Figure 8 is a fragmentary enlarged sectional view through the control switch and lamp mounting.

Figure 9 is a sectional view taken substantially along the line 9—9 of Figure 8, and

Figure 10 is a diagrammatic view of the wiring system.

Referring to the drawings in detail, a plurality of spaced parallel tubes 15 are grouped symmetrically about a longitudinal axis. These tubes are of a size sufficient readily to accommodate dry cells 16 such as are commonly employed in a conventional flashlight. The tubes 15 are of a length sufficient to accommodate several such

2

cells in axial alignment as will be readily understood upon reference to the drawings.

Secured to one end of the group of tubes 15 is a base plate 17 having on one face a group of sockets 18 in which the tubes are sealed to form a gas-tight junction. Attached to the opposite ends of the tubes 15 is a head 19 which is pierced at spaced intervals as at 20 to receive the ends of the tubes, and surrounding the openings 20 are sealing collars 21 in which the tubes are fixed to form a gas-tight junction. As illustrated in Figure 5, the ends of the tubes which enter the openings 20 are wholly open so that the endmost contacts of the cells 16 in the tubes will be accessible through the head. Carried by the head and projecting from the face thereof opposite the face from which the tubes 15 project are headed studs 22 which as illustrated in Figure 4 are symmetrically disposed about the axis above which the tubes 15 are symmetrically disposed and the purpose of these studs will be more fully hereinafter explained. Formed in the head 19 near its outer edge and between each tube are openings 23 for the reception of the threaded studs carried by the hood to be more fully herein-after described. A cylindrical casing 24 surrounds a central opening 25 formed in the head 19 in axial alignment with the longitudinal axis about which the tubes 15 are symmetrically disposed, and this casing is provided at the end opposite the opening 25 with an end wall 26 (Fig. 8) having an axial opening 27 the purpose of which will be more fully hereinafter explained.

Fitted in the opening 25 is a flanged bushing 28 of insulating material in which is molded or otherwise fixedly mounted an internally screw-threaded bushing 29 in which a lamp socket 30 is mounted for longitudinal adjustment as will be readily understood upon reference to Figure 8. A suitable flexible conductor 31 is soldered or otherwise connected to the socket 30, and screwed into the socket 30 is the base 32 of an incandescent electric lamp 33. The end of the socket 30 opposite that into which the base 32 of the lamp 33 enters is closed by a disc 34 of non-conductive material to which is fixed in any suitable manner a disc 35 of a diameter easily to fit within the housing 24 previously described. A central contact 36 extends through the discs 34 and 35 to engage the central contact in the lamp base 32 and riveted or otherwise coupled to the central contact 36 is a spider 37 of conducting material, the radiating legs 38 of which (Fig. 9) are embedded in and lie flush with the surface of the side of the disc 35 opposite that contacting the

disc 34. As illustrated, the ends of the legs 38 terminate short of the periphery of the disc 35 so as to avoid electrical contact with the casing 24. Formed adjacent the outer end of each leg 38 in the exposed face of the spider 37 is a recess 39 and similar recesses 40 are formed in the disc 35 midway between the legs 38.

Rotatably mounted in the opening 27 in the end wall 26 of the housing 24 is a shaft 41 carrying at its inner end a disc 42 to which is riveted or otherwise attached a substantially V-shaped spring contact arm 43 the free end of which is adapted to bear against the exposed face of the disc 35 as will be readily understood upon reference to Figure 8. A lug projects from the spring contact arm 43 for engagement in the recesses 39 or 40 depending upon whether or not the lamp bulb 33 is to be illuminated. Fixed to the end of the shaft 41 opposite that carrying the disc 42 is a thumb-wheel 44 by which the shaft 41 may be rotated. It will thus be seen that the spring contact arm 43 may be moved into or out of contact with any one of the arms 38 merely by rotating the thumb-wheel 44 in either direction.

Fixed to the base 17 at the extreme inner end of one of the tubes 15 is a contact spring 45 (Fig. 10), and fitted in each of the other tubes is a cup 46 of insulating material each of which is provided with a contact spring 47. The contact springs 47 have attached thereto flexible insulated conductors 48, the free ends of which extend outwardly beyond the ends of the tubes and the conductors lie within the tubes adjacent the dry cells 16 as will be readily understood upon reference to Figure 7.

A contact plate designated generally 49 is provided and comprises in the preferred form of the invention a substantially triangular metal plate 50 formed at spaced intervals with key-hole slots 51 which are adapted to receive the outer ends of the headed studs 22 previously described. Riveted or otherwise attached to the plate 50 as at 52 is a plate 53 of non-conductive material such as hard fiber.

Like the plate 50 the plate 53 is also provided with key-hole slots 54 which align with the key-hole slots 51 previously described and attached to the plate 53 adjacent each corner, and insulated from the plate 50 is a contact stud 55 which when the device is assembled bears upon its respective central contact of a group of cells 16 in the tube over which the stud is located. A spring clip 56 has electrical contact with each stud 55 and engaged beneath two of these clips are the termini of the insulated conductors 48 opposite those connected to the springs 47. Engaged beneath the third clip 56 is the terminal of the insulated conductor 31 opposite that which is fixed to the socket 29. By reason of the engagement of the shaft 41 and disc 42 with the casing 24 and wall 26 it is obvious that the spring 43 is grounded, and since the spring 45 is also grounded to the casing through the medium of the base plate 17 it is obvious that when the contact spring 43 is moved into engagement with one of the arms 38 electrical energy will flow through the lamp 33, thus illuminating same.

In order to render the entire unit gas-tight, a suitable gasket 57 is seated on the head 19 and a hood designated generally 58 is seated on the gasket. The hood 58 comprises a shell 59 which conforms to the shape of the head 19 and is provided in its front wall with a window opening 60 which aligns axially with the longitudinal

axis of the device about which the tubes 15 are symmetrically disposed. A cover glass 61 closes the window and is held in place by engagement of the periphery of a suitable reflector 62 preferably of parabolic form. This reflector is held in proper position within the hood 58 through the medium of uniformly spaced clips 63 and formed in the reflector in axial alignment with the cover glass 61 is an opening through which the lamp bulb 33 projects. It will be understood of course, that the plates 50 and 53 are provided with central openings 64 to accommodate the lamp bulb 33 and permit its longitudinal adjustment along the longitudinal axis of the device to enable it to be focused with relation to the reflector 62. Carried by the hood 58 and projecting from the edge thereof which seats against the gasket 57 are externally screw-threaded studs 64 which are adapted to be received in the opening 23, to project therethrough and threaded on the studs are wing nuts 65 by means of which the hood is detachably connected with the head.

In use, it will be understood that the hood 58 may be removed from the head 19 by removing 25 the wing nuts 65 and extracting the studs from the openings 23. Having removed the hood, the plate 49 is next removed by partially rotating it so as to bring the heads of the studs 22 into alignment with the largest portions of the key-hole slots 51 when the plates 49 may be lifted off of the head 19. The dry cells 16 are then introduced into the tubes 15 in the same manner as filling an ordinary flashlight whereupon the plate 49 is replaced so that the studs 55 bear upon the exposed ends of the dry cells 16. The ends of the conductors 48 are then introduced beneath two of the springs 56 and the end of the conductor 31 is introduced beneath the third spring clip 56. In this condition, upon rotating 40 the thumb-wheel 44 a flow of electric current may be established through the lamp 33. The hood 58 is then replaced by projecting the threaded studs 64 through the openings 23 of the head 19, and upon tightening the wing nuts 65 on their respective studs it will be obvious that the hood will firmly be clamped against the gasket 57, thus forming a gas-tight joint with the head.

By removing the hood and turning the socket 50 30 within the threaded bushing 29 it is obvious that the position of the lamp bulb 33 may be adjusted properly to focus the bulb in the reflector 62 so as to produce the desired type of beam.

From the foregoing, it will be obvious that there is provided a flashlight of unusual power and by reason of its gas-tight construction, it may be used under all conditions. Due to the symmetrical disposition of the tubes containing the dry cells about the longitudinal axis of the entire unit, and relatively wide spacing from one another it is obvious that no special carrying arrangement may be required as each tube will serve as a handle and the device may be easily grasped and manipulated without requiring any special attention or orientation other than to direct the beam upon the area to be illuminated.

While in the foregoing there has been shown and described the preferred embodiment of this invention it is to be understood that minor changes in the details of construction, combination and arrangement of parts may be resorted to without departing from the spirit and scope of the invention as claimed.

This is a continuation in part of my co-pend-

ing application, Serial No. 587,852, filed April 12, 1945, which is now abandoned.

I claim:

1. A flashlight which includes a head substantially in the form of an equilateral triangle, said head having a relatively large circular opening adjacent each apex, a tube having one end sealed in each opening, a base substantially in the form of an equilateral triangle fixed to and sealing the ends of the tubes opposite the head, a hood detachably connected to the head, a gasket seated on the head and forming a gas-tight junction with the head, a window in the hood, electrical illuminating means in the hood behind the window, means housed within the tubes to supply electrical energy to the illuminating means and a control switch carried by the head and operable from between the tubes to establish the flow of energy from the energy supply means to the illuminating means.

2. In a flashlight, a group of spaced parallel tubes arranged symmetrically around a longitudinal axis, a base joining and closing said tubes at one end of the group, a head joining the tubes at the opposite end of the group, a hood detachably mounted on the head, a window in the hood in alignment with the axis about which the tubes are grouped, a reflector carried by the hood behind the window, an incandescent electric lamp mounted in the head for adjustment along the longitudinal axis, said lamp projecting into the reflector, power supplying cells within the tubes for supplying energy to the lamp and a switch carried by the head in axial alignment with the lamp selectively to energize or de-energize the lamp.

3. In a flashlight, a group of spaced parallel tubes arranged symmetrically around a longitudinal axis, a base joining and closing said tubes at one end of the group, a head joining the tubes at the opposite end of the group, a hood detachably mounted on the head, a window in the hood

in alignment with the axis about which the tubes are grouped, a socket carried by the head in axial alignment with the window, a nonconducting bushing in the socket, a lamp socket mounted for longitudinal adjustment in the bushing, a group of dry cells in each tube, a lamp in the lamp socket behind the window and means operable axially through the socket carried by the head for establishing the flow of electrical energy from the dry cells through the lamp.

4. In a flashlight, a group of spaced parallel tubes arranged symmetrically around a longitudinal axis, a base joining and closing said tubes at one end of the group, a head joining the tubes at the opposite end of the group, a hood detachably mounted on the head, a window in the hood in alignment with the axis about which the tubes are grouped, a socket carried by the head in axial alignment with the window, a nonconducting bushing in the socket, a lamp socket mounted for longitudinal adjustment in the bushing, a group of dry cells in each tube, a lamp in the lamp socket behind the window and means operable axially through the socket carried by the head for establishing the flow of electrical energy from the dry cells through the lamp, and a reflector carried by the hood behind the window and surrounding the lamp.

MARVIN E. MONTGOMERY.
